UNITED STATES PATENT OFFICE.

GEORGE P. SHERMAN AND ALBERT BONDELI, OF MILWAUKEE, WISCONSIN;
SAID BONDELI ASSIGNOR TO SAID SHERMAN.

CORNER-IRON FOR WOVEN-WIRE-MATTRESS FRAMES.

SPECIFICATION forming part of Letters Patent No. 239,117, dated March 22, 1881.

Application filed September 9, 1880. (No model.)

To all whom it may concern:

Be it known that we, GEORGE P. SHERMAN and ALBERT BONDELI, citizens of the United States, residing at Milwaukee, in the county of Milwaukee and State of Wisconsin, have invented certain new and useful Improvements in Corner-Irons for Woven-Wire-Mattress Frames; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Our invention relates to improvements in corner-irons for woven-mattress frames.

Heretofore the end and side rails forming the frames have been secured to the corner-irons by bolts, two or more heavy bolts being required at each of the four corners of the frame.

The object of our invention is to dispense with the use of the bolts, which end we accomplish by the peculiar construction of the corner-irons, by which they are adapted to be secured to the respective rails in slots or grooves, and the use of bolts becomes unnecessary. Two of the corner-irons at one of the ends of the 3c mattress are adjustable, so that the tension of the mattress may be increased or diminished. The other corner-irons are non-adjustable, and are rigidly fixed to the frame.

Our invention is further explained by reference to the accompanying drawings, in which—

Figure 1 represents an end view. Fig. 2 is a side view of an adjustable corner-iron. Fig. 3 is a front view of the adjustable corner-iron. Fig. 4 is a rear view of the adjustable corner-iron. Fig. 5 is a perspective view of the non-adjustable corner-iron constructed in a single piece.

Two non-adjustable corner-irons are used at one end of the mattress, and two adjustable corner-irons are used at the other end.

In the drawings like parts are represented by the same reference-letters throughout the several views.

A represents one of the side rails, both of 5c which are provided at their respective ends

with slots B B, for the reception of the vertical lugs C C of the respective corner-irons. The lower ends of lugs C are respectively provided with flanges D D, by which they are prevented from being drawn upward through the slots B. F F are the end rails. The corner-irons are secured to the side rails, A, by inserting the lug C in the slot or recess B, when they are respectively drawn firmly toward the centers of the rails, and thus securely retained by the tension of the mattress. When the corner-irons are thus attached to the respective ends of the side rails the end rails are placed at right angles thereto in the recesses G G beneath the V-shaped lug E. Both 65 of the end rails are provided with angular V-shaped grooves, conforming in shape to the lugs E, in which said lugs rest. Thus, as the tendency of the wire mattress is to draw the end rails toward each other, they are drawn thereby back more firmly into the recesses G. It is obvious that by this arrangement a rigid inflexible corner-joint is formed without the aid of bolts, and that the end rails are securely retained above, and in their proper relative position to, the side rails.

In the adjustable corner-irons the lugs C C are made detachable, and are respectively provided with flanges H H.

J is the central part or body of the corner-iron, the lower surface of which is made concave to conform to the convex surface of the upper edge of the side rails. The body J is provided with a dovetailed-shaped slot or recess, I, for the reception of the upper end of 85 the lug C, conforming in shape to the flanges H H, which are loosely fitted therein, and are adapted to be moved and adjusted therein by means of bolt M, nut K, and lug L. Lug L is cast in the same piece with and upon the upper edge of lug C, and is retained thereby in the same fixed relative position to the end of the side rail. The rear end of bolt M engages in a slot in body J. Body J is adapted to be moved forward or backward on flanges 90 H H. Thus, when the mattress is too slack, the nut K is turned forward against the lug L, whereby the bolt M is drawn toward the lug L, carrying with it the end rail, thus increasing the tension of the mattress. If de-

sious to lessen the tension of the mattress, the nut K is turned in the inverse direction.

N represents the ordinary spiral-wire mattress, the respective ends of which are secured 5 to the end rails in the ordinary manner.

Having thus described our invention, we do not claim an adjustable corner-iron or an adjusting-screw for mattress-frames broadly, as we are aware that adjustable corner-irons 10 provided with adjusting-screws are shown in Patents No. 171,042 and No. 224,028.

What we do claim as new, and desire to secure by Letters Patent, is—

1. The improvement in corner-irons for woven-wire-mattress frames herein described, consisting in body J, provided with V-shaped lugs E, adapted to engage upon the edge and upper surface of the end rails, and lug C, having flanges D D, said lugs being adapted to enter 15 gage in slots in the respective ends of the side rails, whereby the end and side rails are rigidly retained in their proper relative position to each other, substantially as and for the purpose set forth.

2. The improved corner-iron herein described, 25 consisting in body J, provided with lug E and recess I, in combination with bolt M, and lug C, provided with flange D, lug L, and flanges H H, lug J being adapted to be moved and adjusted all substantially as and for the purpose set forth.

3. The combination of side rails, A, provided with slots B, the corner-iron consisting in body J, provided with lugs E and C and end rails, F, and the corner-iron J, provided with lug E 35 and recess I, lug C, provided with flange D, lug L, and flanges H H, lug J being adapted to be adjusted substantially as set forth.

In testimony whereof we affix our signature in presence of two witnesses.

GEORGE P. SHERMAN.
ALBERT BONDELI.
